UNITED STATES PATENT OFFICE.

GEORGE S. WILLIAMS, OF NORFOLK, VIRGINIA, ASSIGNOR OF ONE-HALF TO
J. SAUNDERS TAYLOR, OF NORFOLK, VIRGINIA.

PNEUMATIC ACTUATING DEVICE.

SPECIFICATION forming part of Letters Patent No. 746,220, dated December 8, 1903.

Application filed February 21, 1903. Serial No. 144,520. (No model.)

To all whom it may concern:

Be it known that I, GEORGE S. WILLIAMS, a citizen of the United States, residing at Norfolk, in the county of Norfolk and State of

5 Virginia, have invented new and useful Improvements in Pneumatic Actuating Devices, of which the following is a specification.

My present invention relates to a new and improved pneumatic actuating device; and it 10 has for its objects to provide a device of this character that will be simple in construction, inexpensive to manufacture, and quick, positive, and reliable in operation.

One object of the invention is to provide a 15 pneumatic actuating device wherein are employed two air-chests that are subjected to unequal air tensions, which are caused to act upon and operate a diaphragm in a quick, positive, and reliable manner, said diaphragm 20 in turn being caused to actuate any suitable device.

By the term "air-chests that are subjected to unequal tensions" I mean to convey the idea that I may employ air-chests that are 25 either under a state of air-pressure or a state of air-exhaust, thereby enabling the apparatus to be operated either by a pressure or an exhaust bellows.

As a further object my invention has to dispense with the use of springs, gravity, or any 30 other force than air to assist in its operation, thereby eliminating the objectionable features found in other devices of this class and giving a quicker, more positive, and more 35 reliable action.

As a further object my invention has to provide a device which can be adapted to operate any form of mechanism requiring a short, quick, and positive action and can be made 40 in any form or size, according to the nature of the work and the power required.

In the accompanying drawings I show one 45 of the many forms of its application, in which case the diaphragm is caused to throw a shoe on and off a revolving cylinder, a mechanism common in many of the arts. I do not wish to be understood, however, as limiting myself to this specific application of the invention, as it will be obvious that the same may be 50 applied to other uses without departing from the spirit of the invention.

I will now proceed to describe my invention in detail, making frequent reference to the accompanying drawings, which are as follows:

Figure 1 is a vertical longitudinal section showing the arrangement of air-chests, air-chamber, diaphragm, and air connections. Fig. 2 is a front view of the same, with partial transverse section and interior view of 60 air-chest. Fig. 3 is also a vertical longitudinal section showing the device operating a simple form of shoe and cylinder mechanism. Fig. 4 is a modified form of the device wherein a perforated music-sheet is employed to control the air-passage to the atmosphere. Fig. 5 shows the low-tension bellows when collapsed to the point when the check-valve shuts off the connection with other bellows and air-pump.

Reference-numerals are used to indicate the various parts, and similar numerals indicate corresponding parts.

The first part of my invention is shown in Fig. 1 of the accompanying drawings and consists of a diaphragm 10, which can be made of any suitable material. The size and shape of this diaphragm depends upon the work to be done, that shown in the drawings being a simple form made of a light cloth fitted over 80 a circular opening. To this diaphragm is attached a rod 7 to transmit the motion of the diaphragm. This rod can pass out through either air-chest 1 or air-chest 2, according to the work to be done and the direction of stroke 85 desired. On one side of this diaphragm is the air-chest 2, designated the "low-tension" chest, which is maintained at a specified tension by connection with a bellows, as shown in the drawings, and if an exhaust-bellows is 90 employed exerts a continuous pull on this side of the diaphragm. This tension and pull can be varied to suit the work to be performed and is determined by the spring in the bellows, presently to be described, with which 95 it is connected. On the opposite side of this diaphragm is a small air-chamber 3. This air-chamber communicates with the atmosphere by the windway 4, that is controlled by a valve 5 of any suitable construction, and also with the second air-chest 1 by the opening 6. The windway 4 from this air-cham-

ber 3 to the atmosphere must be as large or larger than the opening 6 from the air-chamber 3 to the air-chest 1. The tension in air-chest 1 must be greater than in air-chest 2, 5 and these tensions may be maintained by connections with a high and a low tension bellows, as shown in the drawings, through the connections 8 and 9.

The second part of my invention, which is 10 shown in Fig. 1, comprises a novel method of obtaining two unequal air tensions in separate bellows by the use of one air-pump operating on the stronger bellows. An ordinary type of exhaust-bellows 11 is attached to and 15 connected with the air-chest 12 by the openings 22, from which the air is drawn by the air-pump 13, of the ordinary bellows type, through the openings 23. In this bellows is a spring 18, which determines the tension, 20 and also an escape-valve 20, which is operated by the pin 21 to open when the bellows is collapsed beyond the proper working point, thus maintaining the desired tension in the bellows. Connected with this bellows by the 25 windway 17 is a second bellows 14 of the same ordinary exhaust type, which is attached to and connected with the double-compartment air-chest 15 and 16 by the openings 25 and 26, as shown in the drawings. The air is 30 drawn from the compartment 15 by the air-pump 13 through the windway 17 and exhausts the bellows 14 through the opening 25. The tension in this bellows is determined by the spring 19, and attached to the movable 35 side of this bellows is a check-valve consisting of the movable cone 27, sliding on the guide-pin 28 and supported in position by a coil-spring 29, which is adjusted to close the opening 25 when the bellows is exhausted to 40 the proper working point. Fig. 5 shows the bellows in this position, with the check-cone 27 closing the opening 25, thus shutting off the connection with the other bellows and air-pump and maintaining the desired tension in 45 bellows 14. The tension in compartment 16 is the same as in the bellows 14 by reason of the opening 26 connecting the two. By varying the strength of the springs 18 and 19 the tensions in these two bellows can be adjusted to any desired power, the tension in 11 being greater than in 14.

The air-chest 1 communicates with the bellows 11 and the air-chest 2 communicates with the bellows 14 by the pipe connections 50 8 and 9, as shown in Fig. 1 of the drawings.

Having fully described my invention, I will now demonstrate the principles of its operation.

When the windway 4 is closed, as shown in 60 Fig. 1, the tension in the air-chamber 3 is the same as in air-chest 1 by reason of the opening 6 connecting the two and being greater than the tension in air-chest 2. The diaphragm 10 is drawn over toward 3 with a 65 force depending upon the difference in tensions between 1 and 2 and the surface area

of the diaphragm exposed to the tension. When the valve 5 is open, as in Fig. 3, air is admitted into the air-chamber 3 through the windway 4, and the said windway being as 70 large or larger than the opening 6 supplies all the air that can pass through 6 and thereby releases the tension in air-chamber 3. The tension in chamber 3 being released the diaphragm is drawn over toward air-chest 2 with 75 the full power of the tension in 2. This is the power-stroke of the diaphragm and is the result of the opening of 5 by any desired means, according to the use to which my invention is adopted, whether this be a valve, 80 as shown in Fig. 3, or a perforated music-sheet 30, as shown in Fig. 4. In the drawings, Fig. 3, the diaphragm is shown as operating a common form of mechanism by throwing a shoe 36 on a revolving cylinder 85 32. The rod 7 is connected to one arm of the elbow 33, which is pivoted at 34. The other end of this elbow is attached to the rod 35, carrying the shoe 36, as shown in the drawings. To the upper end of this rod 36 is attached the lever 37 to transmit the motion for any purpose desired. When the diaphragm 10 is drawn over by tension in air-chest 2, as shown in Fig. 3, the shoe is dropped onto the cylinder 32 and revolves with it, being pivoted at 38, the upper end of the rod 35 being thrown in the opposite direction and carrying with it the lever 37, which transmits the motion. As soon as the windway 4 is closed by the valve 5 the tension in the air-chamber 3 is again the same as in air-chest 1, and being greater than in air-chest 2 the diaphragm is again drawn back into its original position, as shown in Fig. 1. It will thus be seen that the moment 5 is opened the diaphragm is operated with a force depending upon the tension in air-chest 2 and the surface area of the diaphragm exposed to it and will continue to operate with that force so long as the windway 4 is open. The moment 105 4 is closed the diaphragm will be released from this position and assume the original position. (Shown in Fig. 1.)

In the foregoing specification and in the drawings I have described and shown a construction wherein the air tensions are caused to act upon a "diaphragm," and I wish it understood that the word "diaphragm" is used in its broad sense to cover a partition, bellows, or hinged flap of any size, shape, or material 115 that will properly respond to the air tensions.

Having fully described my invention and the principles of its operation, I now make the following claims and ask for Letters Patent covering the same:

1. The combination of two air-chests of unequal tensions, an air-chamber communicating by one opening with the high-tension air-chest and with the atmosphere by another opening as large or larger than the first-named 130 opening, means for controlling the opening to the atmosphere, a diaphragm between the

air-chamber and the low-tension air-chest, and means for transmitting the motion of the diaphragm to a part to be actuated.

2. The combination of two air-chests of unequal tensions, an air-chamber communicating by one opening with the high-tension air-chest and by another opening with the atmosphere, means for controlling said last-named opening, a diaphragm between the air-chamber and the low-tension air-chest, and a rod attached to said diaphragm and passing out through one of the said air-chests to transmit the motion of the diaphragm to a part to be actuated.

15 3. In combination with two air-chests, an air-chamber communicating by an opening with one chest and with the atmosphere by another opening as large or larger than the opening in the air-chest, means for controlling the opening to the atmosphere, a diaphragm between the air-chamber and the other air-chest, of two bellows of unequal tension, for the purpose of maintaining the two air-chests at unequal tensions, and means for 25 transmitting the motion imparted to the diaphragm, substantially as and for the purposes shown.

4. The combination of two communicating bellows of unequal tension, an air-pump on the high-tension bellows, and check-valve consisting of a movable cone, sliding on a guide-pin, and supported by a coil-spring, attached to the movable side of the low-tension

bellows in such a manner as to shut off the connection from the air-pump on the high-tension bellows to the low-tension bellows when said bellows is collapsed to the proper working point, substantially as and for the purposes shown.

5. In a pneumatic actuating device, a high-tension wind-chest, a low-tension wind-chest, a diaphragm having its opposite faces exposed respectively to said wind-chest, a windway communicating with said high-tension chest and with the atmosphere, means for controlling said windway, and a rod for transmitting motion having a connection with said diaphragm.

6. In a pneumatic actuating device, a high-tension wind-chest, a low-tension wind-chest, a diaphragm having its opposite faces exposed respectively to the action of said wind-chests, means for transmitting the motion of said diaphragm to a part to be actuated, a windway communicating with said high-tension chest and with the atmosphere, means for controlling said windway, and high and low tension bellows communicating respectively with said high and low tension wind-chests.

In testimony whereof I have hereunto set my hand in presence of two subscribing witnesses.

GEORGE S. WILLIAMS.
